(74) *Attorney, Agent, or Firm* — CANTOR COLBURN LLP

(57) **CLAIM**

The ornamental design for a cover for transport refrigeration unit, as shown and described.

DESCRIPTION

FIG. 1 is a perspective view of a cover for transport refrigeration unit, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof; and,

FIG. 8 is another perspective view thereof, as shown on a trailer unit.

The broken line disclosure forms no part of the claimed design.

1 Claim, 7 Drawing Sheets
